UNITED STATES PATENT OFFICE

THOMAS LA MAIDA, OF UNIVERSITY HEIGHTS, OHIO

ONE-PIECE BATHING SUIT

Application filed October 31, 1932. Serial No. 640,522.

This invention relates to bathing suits, and more particularly to bathing suits of one-garment type; and it is among the objects of the invention to provide a construction which is light and comfortable while providing full coverage, and which makes important savings and advantages in manufacturing. Other objects and advantages will appear as the description proceeds.

To the accomplishment of the foregoing and related ends, the invention, then, comprises the features hereinafter fully described, and particularly pointed out in the claim, the following description and the annexed drawings setting forth in detail certain illustrative embodiments of the invention, these being indicative, however, of but a few of the various ways in which the principle of the invention may be employed.

In said annexed drawings:—

Fig. 1 is a front elevational view of the embodiment of the invention; Fig. 2 is a similar view with a portion broken away at the right of the center line; Figs. 3, 4 and 5 are elevational views of blanks employed in the assembly; Fig. 6 is a perspective view of the blank of Fig. 5 in a further stage of assembly; Fig. 7 is a perspective view, parts being broken away, showing a further stage of assembly; Fig. 8 is a similar view of a modification; Fig. 9 is a like view of a completed garment; and Fig. 10 is a similar view of a modification.

In its general appearance, a bathing suit in accordance with the present invention has the aspects of a garment extending from the shoulders down over the thighs in continuous shirt-like or blouse-like form extending below the bifurcation of the body and providing concealed trunks. A shoulder-thigh or shirt-like garment foundation is first prepared and this may be made up of any usual or preferred fabric, woven or knitted, most usually knitted, and seamed as most conven-

ient, the whole providing shoulder pieces 2 and body portion proper 3.

As shown in Fig. 3, a convenient shaping of the blanks to enter into the garment may involve a blank A of general form to provide the shoulder pieces s, and lower wing-portions w, w. The co-acting blank K is also provided, such that the edge portion a—b may be seamed to the corresponding edge portion c—d of the blank K, the edge portion e—f seamed to the edge portion d—g. The edge portion e—h is seamed to the edge portion b—i, and the edge portion h—j is seamed to the edge k—l, and the edge i—m to the edge l—n. This forms a garment having shoulder straps above and trunk portions below, the same lines being shown in detail in Fig. 7. By also assembling a front and back cover segment M, Fig. 4, a garment as illustrated complete in Fig. 1 results, in which the trunk portions, although formed of co-acting blanks in which blank edges directed rearwardly and blank edges directed forwardly are joined together at a point between the legs to form downwardly extending seams medial- 70 for each leg in the inter-leg trunk walls and concealed within a shirt-like or blouse-like exterior appearance.

In a slightly different procedure, the shirt-like foundation garment may be made up, 75 and within the lower portion of such foundation garment I then apply, securing by sewing or other desired means, inserts F and R at the front and rear. As shown in Fig. 5, such inserts may be formed from a blank B 80 which has a continuous lower edge 4, and a notch n in its upper edge. This blank is fastened together along its edges 5, 6, thus forming the seam 56 in Fig. 6, and it is also cut along the dotted line 7 (Fig. 5) to provide the free edges 8, 9, Fig. 6. The further steps of assembly involve the seaming together of the corresponding edges 8, and the corresponding edges 9, respectively, of the front and rear blank portions, also the se- 90

curing of the outer edges 10, 11, to the corresponding wall of the shirt-like foundation. The final seams 88, 99, 10', 11', 10'', 11'', assemble the form of the garment. In 5 the form shown in Fig. 8, the insert front and rear blanks F, R, are seamed directly to the front and rear walls respectively of the shirt-like foundation garment, the inserts being invisible externally, and having their 10 coacting rearwardly directed edges and forwardly directed edges joined together at a point between the legs to form downwardly extending seams medially for each leg, completing inter-leg portions or close fitting 15 trunks with the coacting outside shirt-like walls, the complete garment being shown also in Fig. 1.

In cases desired, I may also assemble outside front and rear face-pieces or finish- 20 pieces M, these being seamed or attached to the edges 10, 11, of the inserts F, R, and likewise to edges correspondingly positioned in the foundation garment 3, cut-outs therein having been provided for this purpose. In 25 the final assembly of this form, the facing-pieces M in front and behind, are edge-joined with the foundation garment 3, as indicated in Fig. 10, and along the seam lines also with the edge 11, forming the compound seam 11'', 30 and so on throughout, the center seams formed by apposition of the edges 8, 8 and edges 9, 9 respectively, completing the garment, as in Fig. 1.

In the final assembly of the pieces the re- 35 spective shapes involved make possible an easy positioning for machine-seaming operation. If the external finish-pieces M are employed, and these be of the same material as the body-foundation, and properly secured 40 thereto, the line of juncture is scarcely visible, and the entire garment presents the appearance of a construction wholly unitary in character, although attained very advantageously by reason of its elements of assembly. On 45 the other hand, where some variation in appearance is desired, by employing a contrasting material for the face-pieces M, the effect may be correspondingly varied.

It is thus seen that the invention provides 50 a garment of comfortable and advantageous form, aesthetic in appearance, and highly advantageous in manufacture, permitting considerable speed in operation and without undue requirement of skill, and finally very 55 important savings in the material are possible by reason of the forms of elements involved.

Other modes of applying the principle of the invention may be employed, change being 60 made as regards the details described, provided the features stated in the following claim, or the equivalent of such, be employed.

I therefore particularly point out and distinctly claim as my invention:

65 A bathing suit, comprising connected skirt

and trunk portions, the bifurcation of said trunk portion being covered front and rear, close crotch forming portions attached to said trunk portion at the front and rear thereof, said crotch forming portions comprising two 70 inserts connected to form an up and down seam medially of each leg, said trunk portion having openings at the front and rear thereof and said openings having face pieces there- 75 over, the edges of said face pieces, inserts and openings being seamed together in a single seam.

Signed by me this 29th, day of October, 1932.
